UNITED STATES PATENT OFFICE.

WAINWRIGHT B. GERVAIS, OF CHICAGO, ILLINOIS.

FIREPROOF METAL WINDOW FRAME AND SASH.

SPECIFICATION forming part of Letters Patent No. 770,571, dated September 20, 1904.

Application filed March 18, 1904. Serial No. 198,746. (No model.)

To all whom it may concern:

Be it known that I, WAINWRIGHT B. GERVAIS, a citizen of the United States of America, and a resident of Chicago, in the county of 5 Cook and State of Illinois, have invented certain new and useful Improvements in Fireproof Metal Window Frames and Sashes, of which the following is a specification.

The present invention relates to that class 10 of window frames and sashes in which the sashes have horizontal pivotal connection to the frame and are adapted to swing in a vertical plane from an open to a closed condition or vice versa; and the object of the present 15 improvement is to provide a simple, durable, and economical structural formation and combination of the window frame and sash parts adapted to afford a very close joint between the sash and frame with but little incidental 20 friction and to exclude the wind, rain, &c., in a very effective and perfect manner and which is capable of easy manipulation to pivotally open or close the sash in relation to the window-opening of the frame, all as will herein- 25 after more fully appear, and be more particularly pointed out in the claims.

In the accompanying drawings, illustrative 30 of the present invention, Figure 1 is a vertical transverse sectional elevation at line x x , Fig. 2, of a fireproof metal window frame and sash embodying the present invention. Fig. 2 is a front elevation of one side of the window frame and sash with a portion in section to illustrate the pivotal connection of the 35 sash to the frame. Fig. 3 is an enlarged detail vertical transverse section at line x x , Fig. 2, illustrating the top portion of the frame and sash. Fig. 4 is a similar view illustrating the middle portion of said sash and frame. 40 Fig. 5 is a similar view illustrating the bottom portion of the frame and sash. Fig. 6 is an enlarged detail horizontal section at line x' x' , Figs. 1 and 2. Fig. 7 is a similar view at line x^2 x^2 , Figs. 1, 2, and 8. Fig. 8 is an enlarged detail elevation of the pivot portion of 45 the window-frame with the sash shown in dotted lines.

Similar numerals of reference indicate like parts in the several views.

Referring to the drawings, 1 represents the 50 lower horizontal member or sill of the window-frame, formed by a section of structural-iron right-angle bar, one web or flange of which depends vertically to rest upon or be embedded in the ordinary stone sill of the 55 building, as circumstances may suggest.

2 is the upper horizontal member or lintel 60 of the window-frame, formed by a section of structural-iron right-angle bar, one flange or web of which depends to form a shield or shed 60 for the upper end of the opening of the window-frame.

3 represents the vertical side members or 65 jambs of the window-frame, formed by sections of structural-iron right-angle bars, having webs or flanges which project in a lateral direction from the window-frame and are adapted to be built into the wall of the building to substantially and permanently secure 70 the window-frame in place.

The aforesaid series of frame members 1, 75 2, and 3 will be connected together by riveting, welding, or other usual means to constitute a rectangular structure or frame having free inner edges.

4 represents the side rails, and 5 the top and bottom rails, of each window-sash, formed of structural-iron right-angle bars secured together in any usual manner to constitute a 80 rectangular structure.

6 represents sheets of wire-glass, secured in said sash-frames by glazing or confining-strips 7, secured to one series of angle-webs of the series of sash-rails aforesaid and adapted to clamp the sheets of wire-glass 6 against the 85 companion series of angle-webs of said sash-rails, as shown, and where so desired putty flashings or other usual bedding means may be interposed between the surfaces of the glass sheets 6 and the webs and strips aforesaid to secure a wind and water tight joint between the parts.

8 represents pivot-bolts passing through the webs of the vertical right-angle iron side rails of the sash and screwing into the vertical side 95 members or jambs 3 of the window-frame to afford pivotal connection and support for the sash in the window-frame. Such pivot-bolts

will be usually arranged at the mid-height of the sash, as illustrated in Figs. 1 and 2, but may be arranged nearer the upper or lower ends of said sash, as circumstances may require or the judgment of the constructor may direct, and in the preferred form of the present construction, as shown in the drawings, such pivot-bolts will be arranged close to the window-glass 6, and the glazing-strips 7 will be cut away to permit of such arrangement, as illustrated in Fig. 1.

9 and 10 are upper and lower vertical receiving-pockets formed by sections of structural-iron channel-bars, having their base-webs extended laterally past the channels and secured to the vertical side members or jambs 3 of the window-frame, and with a view to permit of a pivotal swinging of the sash in a vertical plane upon the pivot-bolts 8 such pockets are made of a vertical height something less than one-half the vertical height of the sash-frame, and the upper pocket will be located immediately outside the sash-frame, while the lower pocket will be located immediately inside the sash-frame, in the same manner as the outer and upper and the inner and lower stop-rails of the ordinary reversible window of the type in which the sashes swing in a vertical plane. A novel feature of this part of the present invention consists in extending the inner portions 9' and 10' of the respective channel-bars 9 and 10 past each other, as illustrated in Figs. 1, 2, and 8, to constitute bearing or contact surfaces for the vertical end faces of the sash and avoid any gaps at such points through which the wind, &c., might freely enter.

11 and 12 are respectively upper and lower transverse horizontal pockets formed by sections of structural-iron channel-bars having their base-webs extended laterally past the channels and secured, respectively, to the horizontal lintel member 2 and the horizontal sill member 1 of the window-frame and in a double window-frame to an intermediate horizontal cross-rail, as hereinafter more fully set forth. Such horizontal pockets are arranged in respective alignment with the before-described vertical pockets 9 and 10, so as to constitute continuations of the same, as shown.

13 represents vertical tongues formed by sections of structural-iron right-angle bars secured to the vertical edges of the window-sash and having a vertical height equal to that of the upper vertical receiving-pockets 9 and adapted when the sash is in a closed position to occupy the vertical channels or grooves of said pockets to afford a tight joint between the window sash and frame along the upper vertical half of the sash.

14 represents vertical tongues formed by the webs of the vertical right-angle iron side rails 4 of the window-sash, and such tongues

are adapted when the sash is in a closed position to occupy the vertical channels or grooves 65 of the lower vertical pockets 10 aforesaid to afford a tight joint between the window sash and frame along the lower vertical half of the sash.

15 is an upper horizontal tongue formed by 70 a section of structural-iron right-angle bar secured to the upper horizontal edge of the sash and adapted when the sash is in a closed position to occupy the horizontal channel or groove of the upper horizontal pocket 11 75 aforesaid to afford a tight joint between the window sash and frame along the top edge of the sash.

16 is a lower horizontal tongue formed by 80 the web of the right-angle iron horizontal lower rail 5 of the window-sash, and such tongue is adapted when the sash is in a closed position to occupy the horizontal channel or groove of the lower horizontal pocket 12 85 aforesaid to afford a tight joint between the window sash and the frame along the lower edge of the sash.

17 represents elastic bearing-strips of felt or other yielding material arranged in the various pockets 9, 10, 11, and 12 aforesaid and 90 adapted to insure a more perfect joint between the window sash and frame.

18 is a transverse horizontal rail secured the mid-height of the window-frame and which is employed in cases where a pair of sashes are 95 arranged one above the other in a single window-frame. Such transverse rail in the present construction is adapted to carry on its upper surface one of the lower horizontal pockets 12 and on its under surface one of the 100 upper horizontal pockets 11, located in the same relation as that heretofore described in connection with the pockets of the sill and lintel members of the window-frame.

Having thus fully described my said invention, what I claim as new, and desire to secure by Letters Patent, is—

1. In a window, the combination of a window-frame, a sash pivoted in said frame and formed of right-angle bars the webs thereof 110 forming marginal tongues on the lower part of and on one face of the sash, marginally-arranged tongues on the upper part of and on the opposite face of the sash, and formed by sections of right-angle bars secured to the sash, 115 and upper and lower receiving-pockets corresponding with and receiving said tongues in a closed condition of the sash, and consisting of sections of channel-bars having their base-webs extended laterally past the channels and 120 secured to the inner faces of the window-frame, substantially as set forth.

2. In a window, the combination of a window-frame, a sash pivoted in said frame and formed of right-angle bars the webs thereof 125 forming marginal tongues on the lower part of

and on one face of the sash, marginally-arranged tongues on the upper part of and on the opposite face of the sash, and formed by sections of right-angle bars secured to the sash, 5 and upper and lower receiving-pockets corresponding with and receiving said tongues in a closed condition of the sash; and consisting of sections of channel-bars having their base-webs extended laterally past the channels and 10 secured to the inner faces of the window-frame, the base-webs of said channel-bars being also vertically extended past each other to form close bearings for the central marginal portions of the sash, substantially as set forth.

15 3. In a window, the combination of a window-frame the side members of which are formed of right-angle bars the lateral webs of which are adapted to be secured in the wall, a sash pivoted in said frame, marginally-arranged

20 tongues on the upper part of and on one face of the sash, marginally-arranged tongues on the lower part of and on the opposite face of the sash, and upper and lower receiving-pockets corresponding with and receiving 25 said tongues in a closed condition of the sash, and consisting of sections of channel-bars having their base-webs extended laterally past the channels and secured to the inner faces of the window-frame, substantially as set forth.

30 4. In a window, the combination of a window-frame the side members of which are formed of right-angle bars the lateral webs of which are adapted to be secured in the wall, a sash pivoted in said frame, marginally-arranged

35 tongues on the upper part of and on one face of the sash, marginally-arranged tongues on the lower part of and on the opposite face of the sash, and upper and lower receiving-pockets corresponding with and receiving

40 said tongues in a closed condition of the sash, and consisting of sections of channel-bars having their base-webs extending laterally past the channels and secured to the inner faces of the window-frame, the base-webs of said channel-bars being also vertically extended past 45 each other to form close bearings for the central marginal portions of the sash, substantially as set forth.

50 5. In a window, the combination of a window-frame the side members of which are formed of right-angle bars the lateral webs of which are adapted to be secured in the wall, a sash pivoted in said frame and formed of right-angle bars the webs thereof forming

55 marginally-arranged tongues on the lower part of and on one face of the sash, marginally-arranged tongues on the upper part of and on the opposite face of the sash and formed by sections of right-angle bars secured to the sash, and upper and lower receiving-pockets corresponding with and receiving said tongues in a closed condition of the sash and consisting of sections of channel-bars secured to the inner faces of the window-frame, substantially as set forth.

60 6. In a window, the combination of a window-frame, the side members of which are formed of angle-bars the lateral webs of which are adapted to be secured in the wall and the lintel member of which is formed of an angle-bar the web of which depends to form a shed for the upper end of the window-opening, a sash pivoted in said frame, marginally-arranged tongues on the upper part of and on one face of the sash, marginally-arranged tongues on the lower part of and on the opposite face of the sash, and upper and lower receiving-pockets corresponding with and receiving said tongues in a closed condition of the sash, and consisting of sections of channel-bars secured to the inner faces of the window-frame, substantially as set forth.

inner faces of the window-frame, substantially as set forth. 65

6. In a window, the combination of a window-frame, the side members of which are formed of angle-bars the lateral webs of which are adapted to be secured in the wall and the lintel member of which is formed of an angle-bar the web of which depends to form a shed for the upper end of the window-opening, a sash pivoted in said frame, marginally-arranged tongues on the upper part of and on one face of the sash, marginally-arranged tongues on the lower part of and on the opposite face of the sash, and upper and lower receiving-pockets corresponding with and receiving said tongues in a closed condition of the sash, and consisting of sections of channel-bars secured to the inner faces of the window-frame, substantially as set forth. 70 75

7. In a window, the combination of a window-frame, the side members of which are formed of angle-bars the lateral webs of which are adapted to be secured in the wall and the lintel member of which is formed of an angle-bar the web of which depends to form a shed for the upper end of the window-opening, a sash pivoted in said frame, marginally-arranged

80 tongues on the upper part of and on one face of the sash, marginally-arranged tongues on the lower part of and on the opposite face of the sash, and upper and lower receiving-pockets corresponding with and receiving said tongues in a closed condition of the sash, and consisting of sections of channel-bars secured to the inner faces of the window-frame, the base-webs of said channel-bars being extended past each other to form close 85 bearings for the central marginal portions of the sash, substantially as set forth. 90

8. In a window, the combination of a window-frame, the side members of which are formed of angle-bars the lateral webs of which are adapted to be secured in the wall and the

lintel member of which is formed of an angle-bar the web of which depends to form a shed for the upper end of the window-opening, a sash pivoted in said frame and formed

105 of angle-bars the webs thereof forming marginally-arranged tongues on the lower part of and on one face of the sash, marginally-arranged tongues on the upper part of and on the opposite face of the sash and formed by sections of angle-bars secured to the sash, and upper and lower receiving-pockets corresponding with and receiving said tongues in a closed condition of the sash, and consisting of sections of channel-bars secured to the inner faces of the window-frame, substantially as set forth. 110 115 120

9. A window-frame constructed with right-angle side bars having laterally-extending webs at the sides and free inner edges, a right-angle sill-bar having a depending outer web

and a free inner edge, and a right-angle lintel-bar having a depending outer web and a free inner edge.

10. A window-frame having side members which consist of angle-bars the lateral webs of which are adapted to be secured in the wall, and a lintel member which consists of an angle-bar one web of which depends to form a

shed for the upper end of the window-opening, substantially as set forth. 10

Signed at Chicago, Illinois, this 6th day of March, 1904.

WAINWRIGHT B. GERVAIS.
